UNITED STATES PATENT OFFICE.

CHARLES LORBER, OF LOUISVILLE, KENTUCKY.

POCKET KEY CASE.

Application filed November 1, 1926. Serial No. 1145,523.

This invention relates to key cases and has special reference to a combination key and card case.

One object of the invention is to provide a key case of the usual conventional form but having a card pocket or pockets of novel arrangement, which pocket or pockets are accessible without opening the key case proper.

A second important object of the invention is to provide a key case of this character wherein the pockets will be covered from view when the key case is closed, and yet be accessible for the removal or insertion of cards.

With the above and other objects in view as will be hereinafter apparent, the invention consists in general of certain novel details of construction and combinations of parts hereinafter fully described, illustrated 20 in the accompanying drawings and specifically claimed.

In the accompanying drawings like characters of reference indicate like parts in the several views, and:

Figure 1 is a perspective view of the preferred form of combined case.

Figure 2 is a top view thereof.

Figure 3 is a perspective view of a modified form.

Figure 4 is a top view of the modified form.

Figure 5 is a section on the line 5—5 of Figure 4.

Figure 6 is a detail perspective view showing the card pocket forming members separated from the body of the case.

Figure 7 is a detail perspective view partly broken away showing a key holder and the supporting arrangement therefor.

In each of the forms of the invention herein illustrated there is provided a case body consisting of a rectangular piece of suitable material such as leather, imitation leather or the like and this body consists of a back portion 10 and a pair of flaps 11 and 12 arranged laterally with respect to the back portion and foldable one over the other onto the front of the inner side of the back portion. The under flap is provided adjacent its folded part with a snap button member 13 while a co-acting snap button member 14 is carried adjacent the edge of the part 12. Preferably, two pockets are provided each of these pockets is formed from a rectangular strip 15 usually of the same material as the back, and having a notch 16

in its upper edge. Where more than one pocket is formed the strips are graduated in size, the larger strip being sewed at its sides and bottom to the inner flap 11 by a stitch line 17, while the smaller strip is sewed to the larger by a stitch line 18. The double pocket form is shown in Figures 1 and 2 and the single pocket form in Figures 3 and 4. In assembling it is found more convenient to 60 sew the smaller strip 15 to the larger before the latter is secured to the flap 11.

The upper edge of the body 10 is provided with a flap 19 which is doubled over and secured to the front side of the portion 10 by stitching 20 so that a tubular roll 21 is formed for the reception of key holder supporting members 22 flexibly connected together as at 23. Each of these members 22 has swiveled thereto a key holder or hook 24 and slots 25 are provided in the flap 19 for 70 the passage of the shanks of the members 24.

From inspection of the drawing it will be plain that the mouths of the pockets are flush with the upper edge of the flap 11 so 80 that when the flap 12 is closed over the flap 11 and the snap button parts brought together access can still be had to these pockets. Obviously, one of these pockets may be used 85 for calling cards and the other for an identification card and where two pockets are used, it is preferred to form the notches 16 out of registry so that greater ease is afforded for the reception of the thumb and finger in withdrawing a card.

There has thus been provided a simple and efficient device of the kind described and for the purpose specified.

Having thus described the invention, what is claimed as new, is:

1. In combination, a key case body having a back portion and side flaps one of which is foldable over on the front side of the back portion with the back surface of the body in front and the other of which is foldable over the first flap, and a pocket secured to the back surface of the first flap and adapted to be entirely covered by the second flap upon folding the second flap thereover.

2. In combination, a key case body having a back portion and side flaps one of which is foldable over on the front side of the back portion with the back surface of the body in front and the other of which is foldable over the first flap, and a pocket secured to the back surface of the first flap and adapted to be entirely covered by the second flap

upon folding the second flap thereover and having its upper edge flush with the upper edge of the body.

3. In combination, a key case body having a back portion and side flaps one of which is foldable over on the front side of the back portion with the back surface of the body in front and the other of which is foldable over the first flap, a pocket secured 10 to the back surface of the first flap, and a second pocket secured to the outside of the first pocket.

4. In combination, a key case body having a back portion and side flaps one of which is foldable over on the front side of the back portion with the back surface of the body in front and the other of which is foldable over the first flap, a pocket secured to the back surface of the first flap, and a second pocket secured to the outside of the first pocket, said 15 pockets having their upper edges flush with the upper edge of the body.

5. In combination, a key case body hav-

ing a back portion and side flaps one of which is foldable over on the front side of 25 the back portion with the back surface of the body in front and the other of which is foldable over the first flap, and a pocket secured to the back surface of the first flap and having its upper edge flush with the upper 30 edge of the body and entirely covered by the second flap when closed.

6. In combination, a key case body having a back portion and side flaps one of which is foldable over on the front side of 35 the back portion with the back surface of the body in front and the other of which is foldable over the first flap, a pocket secured to the back surface of the first flap, and a second pocket secured to the outside of the 40 first pocket, said pockets having their upper edges flush with the upper edge of the body and entirely covered by the second flap when closed.

In testimony whereof I affix my signature.
CHARLES LORBER.
